DEVICE IN DISHWASHING MACHINE FOR
RECOVERING SILVERWARE AND THE
LIKE

Mario Cavicchioli, New York, N. Y.

Application April 5, 1947, Serial No. 739,705

2 Claims. (Cl. 134—104)

1

This invention relates to a device in dish washing machines for recovering silverware and the like and, more particularly, it refers to a washing and pre-washing device for dishes, glasses and cutlery for use in restaurants and other establishments, and for selectively trapping any escaped silver or small dishware and large particles of waste food material which ordinarily would go into the drain in normal washing operations thereby plugging the drain.

It is an object of this invention to provide a dish and cutlery washing unit adapted to permit removal of waste food matter without the loss of any of the dishes and cutlery from the unit.

One other object of this invention is to provide a novel washing unit provided with easily removable trapping means for preventing the loss of any small objects that are to be washed.

Still another object of the present invention is to provide a dish and cutlery washing machine unit for continuously recirculating the wash water at a predetermined temperature while constantly draining and replenishing the supply of said wash water, said machine having easily removable trap means for reclaiming any cutlery or other ware which may have been washed down towards the drain of the machine, and waste food matter collecting means for preventing clogging of the drainage line connected to the unit.

A more specific object of the present invention is to provide a washing machine for dishes and cutlery containing an easily removable trap and waste food matter collecting device and means forming a seal which will prevent the escape of water from the unit except through normal drainage means provided in said unit.

Another specific object of the invention is to provide a washing machine for dishes and cutlery having sloping means in the washing chamber of the machine for guiding small, washable items and waste food matter into an easily removable receiving device.

Other objects and advantageous features of the invention will become apparent from the following description taken in connection with the accompanying drawings in which:

Fig. 1 is a perspective view of a preferred embodiment of the invention;

Fig. 2 is a vertical sectional view taken on line 2—2 of Fig. 1;

Fig. 2 is a vertical sectional view taken on line 2—2 of Fig. 1;

Fig. 3 is a plan view taken on line 3—3 of Fig. 2;

Fig. 4 is a perspective view of a plurality of

2

removable elements contained in the embodiment shown in Figs. 2 and 3;

Fig. 5 is a plan view taken on line 5—5 of Fig. 6; and

Fig. 6 is a vertical sectional view taken on line 6—6 of Fig. 1.

Referring now to the drawings in which like reference characters denote like parts throughout, there is provided a washing machine 10 consisting of an upper compartment or housing 11 and a lower section or housing 12 mounted preferably on foot rests or pedestals 13, as shown. It will be noted that, for purposes of illustration, the upper and lower housings 11 and 12 respectively are integral with respect to each other whereas, in practice, the housings may be separated from each other in any suitable manner.

Upper housing 11, as shown, consists of the top, side and rear walls, 14, 15, 16 and 17, respectively, while the front 18 of housing 11 is open and is provided with an extension platform 19, as shown. In the interior of said upper housing 11, there is provided a bracket 20 containing spaced rail members 21 and 22 which extend outwardly to the front edge of the platform 19, as shown. Said rails 21 and 22 are provided in the housing for retaining a wire basket or tray 23, as shown in Figs. 2 and 6, which normally, during the washing operation, would contain dishes, saucers, glasses, cutlery, etc. It will be noted that the tray 23 is so constructed that, during the washing and cleaning operation of the contents, the water will easily flow downward into housing 12.

Below said bracket 20 there is provided a bridge plate 24 whose edges are fixed to the bracket 20 and to the walls of the housing by any suitable means, such as spot welding, as shown in Fig. 2. Said bridge plate 24, it will be noted, extends outwardly to platform 19 forming the flooring for same and slopes towards its center constituting a slot type of drain pipe 25 extending into the lower housing 12. Disposed at the top and bottom of the upper housing 11 are sets of spaced perforated pipes 26 and 27 which extend from the interior of rear or end wall 17 to the open or front end 18 of the housing 11. Set 26 is fixed at the ceiling of housing 11 while the other set 27 is fixed in any suitable manner to the lower portion of housing 11. Said sets are interconnected with a main feed pipe 29 extending into the lower housing 12, as shown in Fig. 2, and connected to a recirculating unit or sump pump 30, as shown in Fig. 1. Said feed line 29 is connected to a source of hot and cold water, not shown, and is controlled by a plurality of valves,

not shown. With respect to the extending platform 19, it will be noted that the front edge 31 is provided with a clearance space or recess 32, as shown in Figs. 5 and 6, to permit the attachment thereto of an auxiliary platform 33 for resting thereon additional trays containing washable kitchenware.

Disposed below the housing 11, as heretofore indicated, is lower housing 12 which is provided at the bottom thereof with an overflow pipe 34 in connection with a drain pipe 35. It will be noted that the bottom of housing 12 forms an overflow basin 36 and contains an outlet feed pipe or conduit 37 which is in connection with the recirculating unit or pump 30 which, in turn, forces the water upwardly along the pipe 29 to the top and bottom tiers 26 and 27 of spaced piping in the upper housing 11.

Said lower housing 12, as constructed, is provided with spaced supporting plate members or angle runners, 38 and 39, respectively, extending from the front wall 40 to the rear wall 41. The runners 38 and 39 are connected with vertical plate members 43 and 44 which connect at their upper ends with bottom wall 45 of housing 11. A perforated basket 42, as shown in Fig. 3, slides easily on runners 38 and 39. Said basket 42 may be easily withdrawn from the lower section by merely grasping the handle 46 on the face piece 47 of said basket.

Said basket 42 is provided with opposed rests 48, mounted in any suitable manner on the inside face of front and rear walls 49 and 50 of said basket, for retaining thereon a removable catch tray 51 which extends the full length of the basket 42 and which is disposed directly below the slotted opening of drain pipe 25 of the bridge plate 24, as shown in Fig. 2. Said catch tray 51 is provided with a plurality of holes or openings 52 in its floor 53 to permit drainage of water from the tray. It will be noted that said basket 42 can be easily removed from lower compartment 12. Also said catch tray 51 can easily catch escaping dishes, silver ware and other small items while any waste food matter, escaping from the tray 23 onto tray 51, will be washed over into perforated basket 42 by the continuous stream of wash water flowing down the drain of the bridge plate into the lower compartment 12.

In order to prevent any water from leaking from the lower section 12 during the washing operation, there is provided a drop door 54 forming a platform when in the open position, as shown in Fig. 1, which contains baffle plates or walls 55 and 56, respectively. At its lower edge, said drop door 54 is pivotally hinged to the lower portion of the front wall 40 of the lower section 12. The upper portion of said drop door 54 is provided with a locking member 57 adapted to keep said drop door in closed position with respect to the front wall 40, as shown in Fig. 2. It will be noted that the lower portion of the front wall 40, adjacent the hinged area of the drop door, is provided with a drip gutter 58 extending slightly beyond the width of said drop door 54 so as to collect any water that may seep through the baffle walls of said door. The lower section of front wall 40, disposed opposite gutter 58, is provided with a plurality of openings 59 to permit the drip collecting in the gutter to flow into the bottom 36.

It will be noted that, in order to remove any food refuse that collects on top of catch tray 51 in spite of the wash water flowing over the tray, there is provided a brush member 61, pivotally connected short of one of its ends in wall 62 of

compartment 12. Said member extends through a slotted portion 63 of wall 43 and over the top of tray 51 whereby it can be moved to scrape the top of said tray.

5 In accordance with Fig. 1, it will be noted that I have provided a by-pass pipe 64, shown by the dotted lines, extending from the pipe 65 to the bottom of the bridge plate under the extension platform 19 to which a flexible hose may be attached in order to initially wash off any food waste present among the dishes to be washed in compartment 10.

10 During the washing operation the open front end portion 18 may be covered by any suitable material, such as canvas or waterproof cloth, to prevent the escape of the water from the compartment.

15 From the foregoing description, it will be noted that I have provided a compact, easily operable and economic washing machine in which the water is recirculated and gradually replenished, the temperature of said water being controlled by suitable thermostatic means. Furthermore, a flooring is provided in the upper compartment for 20 sliding cutlery and dishware to a removable unit in the lower section which is adapted to recover any silver ware that may have dropped from the washing tray in the upper compartment. Said tray 51 can be easily handled and removed from 25 the lower section by means of handle members 60. A perforated basket is provided for holding the catch tray and collecting any food waste which is washed over the catch tray into the basket. There is also provided in the lower section, a drop door which, when closed against the 30 front face of the lower section, forms a closure with said front wall preventing water from escaping from the lower section.

35 While a preferred embodiment of the invention has been described and shown herein, it is to be understood that various modifications as to form, use of materials and arrangement of parts may be made without departing from the spirit and scope of the invention as claimed herein.

40 I claim:

45 1. In a dish and cutlery washing machine having a spray washing compartment with an open front end provided with an extending platform integral therewith and having a bracket therein, 50 supporting means in the compartment for retaining dishes and cutlery thereon, conduit means disposed above and below the bracket in the compartment, the improvement comprising a sloping flooring in said compartment below the supporting means having a drain slot, another compartment in connection with the washing compartment provided with a drain, a removable open, 55 perforated basket mounted in the second compartment adapted to collect food refuse and escaping cutlery and the like from the dishes and cutlery being washed, means in connection with the first and second compartments for recirculating washing fluid from one compartment through the conduit means of the other and wash the 60 contents in said first compartment and by recirculation subdivide the garbage particles to permit drainage of same, tray means on the basket aligned with said drain slot in the sloping flooring for catching cutlery and other small objects 65 and receiving the stream of drainage water from the slot and to discharge a major portion of said stream over the upper edges of the tray in order that the stream and garbage therein overflow into the subjacent basket, a closure member 70 hingedly connected to one face of the lower com-

partment, and actuatable brushing means extending through the second compartment adapted for removing and comminuting waste food matter collected by the removable tray means.

2. In a washing machine for china, glassware, silverware and the like, having a spray washing compartment with an open front end provided with an extending platform integral therewith and having a bracket therein, supporting means in the compartment for retaining dishes and cutlery thereon, conduit means disposed above and below the bracket in the compartment, the improvement comprising an apertured inclined floor in said washing compartment, a lower chamber having a normally closed aperture on one side thereof, a removable strainer drawer slidably supported below the aperture of the inclined floor in the washing compartment, said drawer being adapted for removal through said normally closed aperture in the side of said lower chamber, a catcher receptacle supported on the drawer directly below said aperture in the inclined floor, and manually operable brush means supported for a movement through said lower chamber in a plane contiguous with the top of the receptacle to brush debris therefrom into the drawer.
